APPARATUS FOR COOLING CYLINDERS

Russell P. Sweger, Rockford, Ill., assignor to Barber-Colman Company, Rockford, Ill., a corporation of Illinois

Application April 21, 1944, Serial No. 532,089

4 Claims. (Cl. 257—261)

1

This invention relates to baffles for use in the cooling of cylinders, particularly cylinders of internal combustion engines having external cooling fins extending therearound.

The practice in cooling such cylinders is to direct streams of air tangentially past each cylinder, and then lead the air streams toward each other around the cylinder to an intermediate outlet where the streams converge and pass out. There is a continuous dead air pocket formed along an element of the cylinder where the streams converge, and the area of the cylinder exposed to this pocket is not cooled properly.

The primary object of the present invention is to overcome this difficulty by providing a novel means for baffling the cylinder.

Another object is to divide the two air streams into separate parts and to distribute the parts to a plurality of outlets which are spaced axially and circumferentially of the cylinder thereby avoiding a continuous dead pocket along an element of the cylinder.

The invention also resides in the novel construction of the baffle for carrying out the foregoing objects.

Other objects and advantages of the invention will become apparent from the following detailed description taken in connection with the accompanying drawings, in which

Figure 1 is a fragmentary elevational view of a radial type internal combustion engine equipped with baffles constructed in accordance with the present invention.

Figs. 2, 3, and 4 are enlarged fragmentary sectional views taken respectively along the lines 2—2, 3—3, and 4—4 of Fig. 1.

Fig. 5 is a fragmentary perspective view of one of the cylinders and its baffle.

Fig. 6 is a fragmentary cross-sectional view taken along the line 6—6 of Fig. 1.

While the invention is susceptible of various modifications and alternative constructions and of being practiced in various ways, I have shown in the drawings and will herein describe in detail the preferred embodiment and manner of carrying out the invention. It is to be understood, however, that I do not intend to limit the invention by such disclosure, but aim to cover all modifications, alternative constructions and methods falling within the spirit and scope of the invention as expressed in the appended claims.

In the drawings, the invention is illustrated in connection with the cooling of a cylinder 10 of a so-called radial internal combustion engine, each cylinder having fins 11 lying in planes per-

2

pendicular to the cylinder axis and closely spaced to each other so as to provide surfaces of substantial area over which a cooling medium such as air may be directed to cool the cylinder. In accordance with the usual practice, a baffle 12 constructed of sheet metal is mounted on the engine in any suitable way and formed with annularly spaced semi-cylindrical members 13 which fit closely around the rear or down stream sides of the cylinders and are connected by intervening imperforate webs 14. With this arrangement, a body of air directed against the front of the engine is divided by the cylinders 10 into streams A and B which flow around the cylinders into the circumferentially extending spaces defined by the fins 11, the external cylinder surface, and the baffle member 13.

The present invention aims to avoid the formation of a continuous dead spot along the cylinder at the points where the streams A and B impinge against each other. To this end, the two air streams flowing around each cylinder are divided into a plurality of corresponding increments which converge upon each other and on the rear side of the cylinder and flow out through openings 15 and 16 which are spaced apart both circumferentially and axially of the cylinder so as to stagger the dead areas 11 and 18 of the adjacent pairs of impinging stream increments.

To carry out this method, the outlet openings 15 and 16, which are somewhat elongated in a circumferential direction, are arranged in two rows extending parallel to the cylinder axis but circumferentially spaced apart so as to leave imperforate areas 15^a of the baffle 13 intervening between the holes 15, and similar imperforate areas 16^a between the holes 16 of the other row.

The holes 15 and 16 are formed by striking metal out of the baffle member 13 to form flanges 15^b and 16^b projecting toward the cylinder from the concave side of the baffle. These flanges thus extend circumferentially, and their spacing is correlated with the spacing of the fins 11 so that the adjacent flanges of each row register and lie substantially in abutment with alternate ones of the cylinder fins (see Fig. 2).

It will be observed that the flanges 16^b cooperate with the intervening baffle area 16^a to define a circumferentially extending passage for carrying a portion of the air stream A past the adjacent holes 16 to a hole 15 which lies in the same axial plane as this portion a of the stream. Similarly, the adjacent fins 15^b cooperate with intervening areas 15^a to define passageways which

carry portions *b* of the air stream *B* past the holes *15* and deliver these stream increments to the correspondingly spaced holes *16* at which point the increments *b* converge upon the stream increments *a* and are discharged outwardly through the holes *16* as illustrated in Fig. 3. In a similar way, the increments *b'* of the stream *B* and the increments *a'* of the stream *A* which are carried past the holes *16* converge upon each other as illustrated in Fig. 4 and are diverted outwardly through the openings *15*. The dead areas *18* formed by the converging stream increments *a'* and *b'* are spaced circumferentially around the cylinder *10* from the pocket *17* formed between the converging streams *A* and *B* with the result that there is no continuous element of the cylinder exposed to a dead area. Accordingly, each area of the cylinder *10* which is exposed to one of the dead air areas *17* or *18* is of comparatively small dimension and is flanked on all four sides by areas of the cylinder which are exposed to the moving area and, therefore, is cooled by thermal conduction from the latter areas. As a result, the temperature of the cylinder opposite the air outlets is reduced considerably, and the cylinder is therefore cooled more effectively. Moreover, the flanges *15^b* and *16^b* divide the air streams *A* and *B* and guide the increments to the outlets in well defined paths thereby avoiding turbulence which further contributes to the cooling efficiency.

I claim as my invention:

1. A device for baffling a cylinder comprising a semi-cylindrical member adapted to fit around one side of said cylinder in spaced relation thereto to provide air passages between the cylinder and the concave surface of said member, said member having intermediate its edges two rows of holes therein staggered along an element of the semi-cylinder, and circumferentially extending flanges projecting from said concave surface at opposite edges of said holes and disposed substantially perpendicular to such surface, the adjacent flanges in each row of holes cooperating with each other and the intervening imperforate portion of said member to define a passage for directing an air stream circumferentially along said concave surface and past the holes of such row to a hole of the other row.

2. A device for baffling a cylinder having axially spaced peripheral cooling fins, said device comprising a semi-cylindrical member adapted to

fit around one side of said cylinder adjacent said fins and having intermediate its edges rows of holes therein staggered along an element of the semi-cylinder with the spacing of the holes in each row correlated with the spacing of said fins, and circumferentially extending flanges projecting from the concave surface on opposite sides of said holes and spaced apart to register individually with said fins, the adjacent flanges in each row of holes cooperating with each other and the fins with which they register to define a passage for directing an air stream circumferentially along said concave surface and past the holes of such row to a hole of the other row.

3. A baffle for directing the flow of a cooling medium around a cylinder comprising, a piece of sheet metal curved to fit around the exterior of said cylinder and having the metal thereof struck inwardly from the concave side of the piece to form rows of holes staggered relative to each other, the struck-out metal forming flanges at opposite edges of the holes and extending circumferentially of the baffle whereby the adjacent flanges coact with each other to form an air passage.

4. A baffle for directing a cooling medium around an engine cylinder comprising an arcuate piece of sheet metal having the metal thereof intermediate its edges struck inwardly from the concave side of the piece to form rows of holes staggered relative to each other, the struck-out metal forming generally parallel flanges disposed at opposite edges of the holes and substantially perpendicular to said concave side and extending circumferentially of the baffle whereby the adjacent flanges form an air passage between them.
